(57) **CLAIM**

The ornamental design for a smart phone case strap, as shown and described.

DESCRIPTION

FIG. 1 is an upper isometric view of a smart phone case strap;

FIG. 2 is a left side view of a smart phone case strap;

FIG. 3 is a right side view of a smart phone case strap;

FIG. 4 is a front view of a smart phone case strap;

FIG. 5 is a rear view of a smart phone case strap;

FIG. 6 is a top view of a smart phone case strap;

FIG. 7 is a bottom view of a smart phone case strap;

FIG. 8 is an external view of a smart phone case strap attached to an exemplary smart phone case; and,

FIG. 9 is an internal view of a smart phone case strap attached to an exemplary smart phone case.

The longer dash-dash broken lines depicting a cell phone case in FIGS. 8 and 9 depict environmental subject matter that forms no part of the claimed design.

The shorter dash-dash broken lines illustrate stitching that does form part of the claimed design.
